UNITED STATES PATENT OFFICE.

WILLIAM D. ANTRIM, OF GLOUCESTER, NEW JERSEY, ASSIGNOR TO WELSBACK COMPANY, OF GLOUCESTER, NEW JERSEY, A CORPORATION OF NEW JERSEY.

DESIGN FOR A GAS HEATER.

60,747.

Specification for Design.

Patented Apr. 4, 1922.

Application filed July 12, 1921. Serial No. 484,209. Term of patent 3½ years.

To all whom it may concern:

Be it known that I, WILLIAM D. ANTRIM, residing at Gloucester, in the county of Camden and State of New Jersey, have invented a new, original, and ornamental Design for Gas Heaters, of which the following is a specification, reference being had to the accompanying drawing, forming part thereof,

in which the figure is a perspective view of a gas heater embodying my new design.

I claim:

The ornamental design for a gas heater, as shown.

In testimony whereof, I have hereunto set my hand.

WILLIAM D. ANTRIM.
